UNITED STATES PATENT OFFICE.

JOHN F. STANDISH, OF WINTHROP, MASSACHUSETTS, ASSIGNOR TO UNITED SHOE MACHINERY COMPANY, OF PATERSON, NEW JERSEY, A CORPORATION OF NEW JERSEY.

HEEL-ATTACHING MACHINE.

1,208,853.

Specification of Letters Patent. Patented Dec. 19, 1916.

Application filed April 19, 1915. Serial No. 22,357.

To all whom it may concern:

Be it known that I, JOHN F. STANDISH, a citizen of the United States, residing at Winthrop, in the county of Essex and State 5 of Massachusetts have invented certain Improvements in Heel-Attaching Machines, of which the following description, in connection with the accompanying drawings, is a specification, like reference characters on 10 the drawings indicating like parts in the several figures.

This invention relates to machines for attaching rubber heels or lifts to boots and shoes.

15 In securing a rubber heel to a shoe it is frequently desired, in addition to the attaching nails, to cement the heel and leather part together. Preliminarily to the nail driving operation the cemented heel and the 20 leather part are subjected to pressure to force them into intimate contact and in this operation a rubber heel tends to bulge laterally. Such bulging produces a relative transverse movement between the adjacent 25 cemented faces of the leather and of the heel and this movement has the effect of rolling the cement into strings and so destroying its effectiveness.

An object of the present invention is to 30 provide means for holding a rubber heel in contact with the leather part to which it is to be attached by nails without permitting the objectionable transverse movement of the cemented face of the heel during the operations of subjecting the heel to pressure 35 and driving the attaching nails. It is important, however, the certain portions of the heel should be permitted to bulge in order that the material adjacent to the attaching nails 40 may flow when displaced by the drivers. Otherwise the heel will be mutilated when the drivers are forced below the tread surface of the heel to embed the attaching nails therein.

45 To this end an important feature of the invention consists in holding means shaped to engage the marginal portion of a heel adjacent to its cemented surface while permitting the heel to bulge laterally above its 50 confined area.

It is frequently desired to attach a rubber heel to a curved surface such as the heel seat of a shoe and, in order to cause the cemented surface of the heel to adhere to the leather

part over its entire area, it is necessary to 55 bend the heel into conformity with such curved surface.

The present invention contemplates, as another of its features, the provision of means for engaging the tread face of the 60 heel adjacent to its margin in such manner as to bend the heel into conformity with the curved surface of the leather part when the heel is subjected to pressure.

In operating upon rubber heels as they 65 are now supplied by the manufacturers there is likely to be found an appreciable variation in the location of the attaching nails with which the heels are loaded before they are presented to the attaching machine. In 70 order to allow for such variations the present invention contemplates, as another of its features, the provision of a gang of drivers including several drivers of oval cross-section so disposed as to cover the area 75 in which each of the attaching nails is likely to be encountered.

These and other features of the invention will be best understood and appreciated from the following description of a preferred embodiment thereof selected for purposes of illustration and shown in the accompanying drawing, in which,—

Figure 1 is a view in front elevation, partly in section, of a heel attaching machine embodying the present invention; Fig. 2 is a view in perspective of the driver gang; Fig. 3 is a sectional view of a rubber heel and the parts adjacent thereto; Fig. 4 is a view in perspective of the heel holding 80 member, and Fig. 5 is a view in perspective 90 showing an attached heel as it appears while under pressure.

The invention is herein illustrated as embodied in the well-known American lightning nailing machine but it is not limited in its application to that machine or to machines of any particular type. Only sufficient of the machine is herein illustrated to disclose fully the present invention, the parts 95 of the machine not shown comprising only such as are well known in nailing machines of this type.

The frame 10 is provided with a stationary die plate 12 through which extend vertical passages 14 for the drivers. Beneath the die plate is supported a jack 16 upon which the shoe to be heeled is placed by the

operator. Mechanism, not herein shown, is provided for elevating the jack toward the die plate 12 when it is desired to subject the work to pressure. The jack herein shown is constructed to support a shoe on a last 18 with its heel seat portion in alignment with and beneath the driver passages 14.

The machine frame 10 is provided with vertical bearings in which reciprocate a pair 10 of side rods 20 carrying at their upper ends a cross head 22. The cross head is provided on its lower surface with transverse ways for the reception of the driver block 24 in which the individual drivers 26 are rigidly 15 set. The rear driver is of circular cross-section and the remaining drivers are of oval cross-section and are set with their major axes extending divergently.

The die plate 12 is provided on its lower 20 surface with undercut ways 29 for the reception of the heel holding member 28. The heel holding member has opposite parallel edges shaped to slide in the guideways 29 and a socket 31 in one edge for the reception 25 of a spring locking pin 33.

The locking pin 33 maintains the holding member in a proper position and permits its removal when it is desired to substitute another holder of a different size.

30 The holder 28 is cut out at its center and has annular surfaces shaped to fit the marginal surface of a rubber heel of a given size. Other interchangeable holding members are provided having dimensions appropriate for receiving heels of different sizes. When in position beneath the die plate 12 the lower portion of the holder member 28 comprises a U-shaped flange 30 shaped to fit the curved marginal surface of a heel adjacent to that surface of the heel which is to lie upon the leather part of the shoe. Above the flange 30 the holding member is provided with an annular groove or slot 32 and above the slot 32 is formed a second flange 45 34 beveled inwardly on its lower surface. The breast portion of the holding member 28 comprises a beveled bar 36 curved in contour to correspond to the transverse curve of the shank of a shoe.

50 In the accompanying drawings the rubber heel to be attached is shown as having a beveled breast surface and as being adapted for attachment directly to the outsole of a shoe. It will be understood, however, 55 that it is within the scope of the invention to adapt the heel holding member for rubber heels of other shapes, to be attached directly to an outsole or to a leather deck previously attached to an outsole, or for a rubber top lift. Moreover the term "rubber heel" is used broadly for convenience to designate any heel or lift of resilient characteristics.

60 In attaching a heel of the character herein disclosed the shoe is first placed upon the

jack 16 with the heel seat portion of the outsole beneath the heel holding member 28. A heel which has been previously loaded with attaching nails 42 is then placed within the holder with the attaching nails projecting 70 upwardly into the driving passages. The lower surface of the heel and preferably the heel seat portion of the sole have been coated with cement which is in condition to secure together the two surfaces when they are 75 pressed together. The jack is then elevated to press the rubber heel and sole firmly together. In this operation the marginal surface of the heel is confined by the flange 30 adjacent to the sole 43 so that there is no 80 transverse movement between it and the sole. Above the flange 30 the groove 32 permits the bulging of the material of the heel. The beveled surface of the upper flange 34 tends to bend the rubber heel downwardly 85 above its margin so that it will conform accurately to the curved heel seat surface of the sole. The beveled and curved breast bar 36 act similarly upon the breast portion of the heel laying it firmly in place against the 90 curved shank and causing the lower surface of the rubber heel to adhere to the sole out to the extreme edge of the heel. When the work has thus been subjected to pressure the side rods 20 are pulled downwardly and the drivers 26 operated to drive the attaching 95 nails through the sole of the shoe and clench them upon the portion 18 of the jack. The attaching nails, as shown in Fig. 3, pass through washers which are incorporated in 100 the rubber heel during its manufacture and the throw of the drivers is such that the heads of the attaching nails are embedded in the material of the rubber heel, until they 105 rest upon the washers.

As the location of the washers is likely to vary somewhat in the different sizes of heel to be attached the drivers are made of large cross-section and are so arranged as to cover the areas in which the attaching nails are 110 most likely to be encountered. As this variation is not likely to occur in the case of the rear nail of the gang the rear driver may be of circular cross-section as shown in Fig. 2. After the attaching operation the drivers are elevated and the jack lowered thus releasing the pressure upon the rubber heel. The latter therefore contracts to its normal shape and is drawn downwardly out of its holder with the shoe to which it has 115 been attached.

120 It will be noted that when the heel 40 is bent into conformity with the curved heel seat of the shoe the points of the attaching nails 42 are inclined inwardly. This preliminary positioning of the nails is advantageous in that it prevents the nails from being driven out through the sides of the shoe as might occur if they were free to assume their own direction.

Having thus described my invention, I claim as new and desire to secure by Letters Patent of the United States:—

1. In a heel attaching machine, means for pressing a resilient heel upon a shoe, and means for confining the heel about its margin adjacent to the shoe, said latter means being constructed and arranged to permit lateral expansion of the heel above its confined area.
2. In a heel attaching machine, a jack and heel engaging plate relatively movable to press a cemented resilient heel upon a shoe, and means for confining the heel about its margin adjacent to the cemented surface of the heel while permitting the heel to bulge laterally above its confined area.
3. In a heel attaching machine, a jack and heel engaging plate relatively movable to press a resilient heel upon a shoe, and a ring member shaped to engage the periphery of the heel and having a groove in its inner face to permit bulging of the heel in that portion of its area located opposite to the groove.
4. In a heel attaching machine, relatively movable members for pressing a resilient heel upon a shoe, and a ring member shaped to confine the heel against bulging laterally adjacent to its flat faces and having a groove for permitting such bulging intermediately.
5. In a heel attaching machine, relatively movable members for pressing a resilient heel upon a shoe, a gang of drivers movable to force attaching nails below the tread surface of the heel, and a holding member shaped to confine the heel against bulging laterally adjacent to the shoe and having a groove to permit such bulging below the tread surface of the heel.
6. In a heel attaching machine, relatively movable members for pressing a resilient heel upon a shoe, and a heel holding member having two narrow flanges shaped to engage the marginal surface of a heel and being spaced from each other.
7. In a heel attaching machine, relatively movable members for pressing a resilient heel upon a curved surface, and a heel holding member shaped to engage the marginal surface of the heel and having a beveled flange arranged to overlie the tread face of the heel adjacent to its margin.
8. In a heel attaching machine, a jack and die plate relatively movable to press a resilient heel having a beveled breast surface upon a curved surface, and a presser member beveled to correspond to the breast surface of the heel and curved to bend the breast portion of the heel into contact with said curved surface.
9. In a heel attaching machine, a die plate, a holder for a rubber heel disposed beneath the die plate and having a beveled flange arranged to be interposed between the margin of a heel in the holder and the die plate, and a curved flange spaced from the beveled flange and serving to confine the heel at its marginal surface adjacent to the shoe.
10. In a heel attaching machine a holder for a heel loaded with attaching nails, and means for subjecting the heel to pressure and at the same time bending it transversely to incline the attaching nails inwardly.
11. In a heel attaching machine, a movable jack, a holder for maintaining a loaded flexible heel in alignment with the heel seat of a shoe on the jack and having means for bending the heel transversely to incline the attaching nails when the jack is moved, and nail drivers constructed and arranged to operate while the nails are so inclined.
12. In a heel attaching machine, a die plate, a heel holder disposed adjacent the die plate and shaped to hold a flexible heel with its tread face spaced from the die plate, and a jack movable to force the center portion of the heel into contact with the die plate, thereby bending the heel to fit a convex heel seat.

In testimony whereof I have signed my name to this specification.

JOHN F. STANDISH.
